(57) **CLAIM**

The ornamental design for a sensor for excrement detection, as shown and described.

DESCRIPTION

FIG. 1 is a front, right side, top perspective view of a sensor for excrement detection showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the article and form no part of the claimed design.
